UNITED STATES PATENT OFFICE.

FRANK R. EVANS, OF ZANESVILLE, OHIO.

GAUNTLET-CUFF AND METHOD OF PRODUCING THE SAME.

1,295,720.

Specification of Letters Patent.

Patented Feb. 25, 1919.

Application filed February 7, 1918. Serial No. 215,887.

To all whom it may concern:

Be it known that I, FRANK R. EVANS, a citizen of the United States, residing at Zanesville, in the county of Muskingum and 5 State of Ohio, have invented certain new and useful Improvements in Gauntlet-Cuffs and Methods of Producing the Same, of which the following is a specification.

This invention relates to apparel manufacturers and has as its object the production 10 as a new article of manufacture, of an apparel blank possessing features desirable from a commercial point of view, and a novel method of producing such a blank. 15 While the present invention is related more especially to the production of gauntlet cuffs, the principles thereof may be followed in the production of various articles of wearing apparel consisting of two or more plies 20 of material which it has been heretofore customary to unite by one or more lines of stitching. Therefore, while the specific disclosure of the invention in the description which is to follow will be directed solely to 25 the production of gauntlet cuffs it will be understood that the invention is not restricted to this particular adaptation.

Ordinarily gauntlet cuffs are produced in the nature of blanks of the proper shape, 30 each blank consisting of a facing ply and a lining ply, these plies being united to each other by one or more lines of stitching extending longitudinally between the outer and inner edges of the blank and a line of 35 over-edge stitching at both the inner and outer edges of the blank. The first-mentioned lines of stitching, which are equivalent to quilting, serve, of course, to unite the intermediate portions of the plies of the 40 cuff blank so as to hold these portions together and thus assist in retaining the shape of the cuff when the cuff is crushed. The outer and inner edges of the plies are united by the lines of over-edge stitching both as a matter of security and also to produce an 45 ornamental effect. It is customary for the wholesaler or glove manufacturer, who is to place gauntlets of his particular design upon the market, to supply the gauntlet cuff manufacturer with the cloth or other material from which the cuffs are to be made and to also furnish the manufacturer with the 50 thread necessary for the stitching together of the plies of the cuff, the manufacturer on the other hand furnishing the necessary ma- chines for carrying out the operations of cutting the material into the blanks of required form and stitching together the plies of the blanks to produce the finished article. In the instance of the inexpensive varieties 55 of gauntlets, the wholesaler's profit on each dozen is ordinarily not more than two or three cents, the cost of material, namely, the material from which the blanks are formed and the thread, being a considerable item of 60 expense. It will be apparent, therefore, that if the cost of the thread were eliminated, the wholesaler's profit would be considerably increased, considering the fact that he usually requires the manufacture of several thousand dozens of cuffs per day. The stitching together of plies comprising the cuff blanks also entails the waste of a considerable quantity of thread, for it is customary to run, 65 for example, a line of stitching through the plies of one cuff blank and then follow this blank on the machine with another blank through the plies of which a corresponding line of stitching is to be run, and the thread which spans the gap which must necessarily 70 occur between the receding end of the first blank and the advancing end of the second mentioned blank is an absolute waste. Furthermore, if stitches are skipped in the 75 operation of the sewing machine, it is necessary to stop the machine, move the cuff blank back to such a position that the presser foot and needle will overlap, to a considerable distance, a portion of the line of stitching being run, and then again begin the step 80 of stitching. As a result the new line of stitching will overlap the old line and this involves a waste of thread. Furthermore, over-edge stitching requires considerably 85 more thread than is necessary in running a line of ordinary stitching and, therefore, in over-stitching the edges of the cuff blank considerably more thread is employed than is actually necessary to unite the edges of the plies comprising the blank. The present 90 invention, therefore, aims to save to the wholesaler of articles of the class mentioned, not only the cost of the thread ordinarily wasted, but also the cost of the thread which has heretofore been considered absolutely 95 necessary to be employed in properly joining together the plies of the article. Aside from this saving in material and reduction in the cost of production of the article, the 100 invention aims to provide for the production 105 110

of the article in equally as durable a condition as though its plies were stitched together, and with the same artistic appearance as possessed by a similar one of the 5 articles, in which the plies are united by lines of stitching. In other words, the invention aims to provide for the production of a gauntlet cuff or like apparel blank comprising plies united without the employment 10 of stitching and at the same time possessing every appearance of being neatly and artistically stitched. Thus by following the principles of the invention the wholesaler may be supplied with the articles at a much 15 lower cost than at present, as he is relieved of the necessity of furnishing the manufacturer with thread for the purpose of stitching together the plies of the article, and on the other hand the manufacturer benefits 20 as he is relieved of the expense incident to the operation and upkeep of expensive sewing machines. The invention contemplates that the finished article shall have its plies united as securely as though stitched together and in such manner as to obtain a 25 reinforcement of the article as a whole to a greater extent than if the plies were united by stitching and, consequently, the purchaser of gauntlets having their cuffs manufactured in accordance with the invention is 30 also benefited as he is furnished with a more substantial and durable article than heretofore, and if the wholesaler sees fit, at a lower cost.

35 Aside from the disadvantages above pointed out for the use of thread in securing together the plies of gauntlet cuff blanks, there are other disadvantages which will now be explained. As above stated lines of 40 stitching are ordinarily run longitudinally of such a blank through the intermediate portions of the plies comprising the same so as to hold these portions of the plies together and assist in retaining the shape of 45 the cuff when crushed or crumpled. However, the said portions of the plies are only united along an extremely narrow line which is the line of stitching and, therefore, these 50 lines of stitching add little if anything to the stiffness of the completed cuff and assist but slightly in preventing crumpling thereof. Furthermore, in running the lines of stitching the material of the plies is repeatedly punctured by the machine needle 55 and thus is weakened along each line of stitching. While this would be hardly perceptible in the instance of thin or soft cloth, it is very noticeable in the instance of gauntlet cuffs, the plies of which are ordinarily of 60 drilling or other heavy and relatively stiff cloth, and in fact the plies are so weakened along the lines of stitching that the material very readily bends along these lines and the completed cuffs comprising several plies may be folded or broken down along such lines

as readily as though scored or partly cut through at the lines of stitching. Therefore, in the ordinary methods of manufacturing gauntlet cuffs the cuff is greatly weakened by the intermediate lines of stitching passing through its plies. The present invention, therefore, aims further to disclose a method whereby the plies comprising such a cuff blank may be united at their intermediate portions in such a manner that their 70 said portions will be additionally stiffened and reinforced, thus not only overcoming the disadvantages attending the union of such plies by lines of stitching, but at the same time securing new advantages and providing an article in every way more desirable both to the wholesaler and to the pur- 75 chaser. In fact from the specific description which is to follow it will be apparent that by following the principles of my invention 80 there may be produced a gauntlet cuff more substantial than the ordinary stitched cuff, possessing none of the disadvantages of the latter, and presenting many new advantages 85 which render the article as a whole far 90 superior to a cuff produced by the old methods.

In the accompanying drawings:

Figure 1 is a plan view of one form of cuff blank produced in accordance with the 95 present invention;

Fig. 2 is a sectional view on the line 2—2 of Fig. 1;

Fig. 3 is a perspective view of the blank shown in Fig. 1, the plies at one end of the 100 blank being partly separated;

Fig. 4 is a view similar to Fig. 1, illus- 105 trating a modified form of blank;

Fig. 5 is a view similar to Fig. 2 taken on the line 5—5 of Fig. 4;

Fig. 6 is a perspective view of the blank produced by the invention united to the wrist portion of a gauntlet;

Fig. 7 is a view similar to Fig. 4 illustrating a further modified form of the blank; 110

Fig. 8 is a sectional view on the line 8—8 of Fig. 7.

A cuff blank produced in accordance with the present invention may consist of any desired number of plies and in the forms of 115 the invention shown in Figs. 1 to 5 inclusive, the blank comprises a facing ply 1 and a lining ply 2. These plies may be of like material or each of a different kind of material if found desirable. Ordinarily the facing ply 1 will be of a fair grade of cloth possessing any desired degree of stiffness and the lining ply 2 will be preferably of a heavy cloth which is relatively thick or stiff and if desired of a cheaper quality. In carrying out the invention, the two plies in the form of relatively long strips may be assembled and united and subsequently cut into blanks of suitable length, or if desired 125 the plies may be initially cut into blank 130

form and then assembled. As above stated it has been heretofore customary to unite the plies at both their inner and outer edges with lines of over-edge stitching and to further unite their plies by parallel lines of stitching extending longitudinally of their intermediate portions. The present invention also contemplates uniting the plies along these lines but by the employment of means other than lines of stitching, and in carrying out the method of the invention, assuming that the plies are initially in the nature of long strips of material, for example, in roll form, one of the plies, as for example, the lining ply 2, has applied to its inner face, or in other words, that face which is to contact the facing ply 1, lines or relatively narrow longitudinal zones of adhesive, as indicated by the numerals 3, 4, 5 and 6. The zones of adhesive 3 and 6 are located respectively at the outer and inner edges of the said face of the ply 2 and the zones 4 and 5 of adhesive extend parallel to each other and to the zones 3 and 6 and longitudinally of the ply or strip at the intermediate portion thereof. If desired one of the intermediate zones 4 or 5 may be omitted and on the other hand the number of such intermediate zones of adhesive may be increased if found desirable. The adhesive which is employed is of a water-proof and heat-proof character and as the strip from which the plies 2 are to be cut is supplied with the adhesive in the zones 3, 4, 5 and 6, this face of the strip is brought into firm contact with the inner face of the strip from which the plies 1 are to be formed, pressure being preferably applied at such time so as to force the adhesive into the interstices of the strips, thereby securing a firm union of the strips to each other. It will be understood that adhesive may be applied to the inner face of the strip comprising the plies 1 instead of to the strip comprising the plies 2, or that adhesive may be applied to the contacting or mutually engaging faces of both of the strips. In applying pressure to the strips in the manner stated above, the strips may be passed between heated presser rolls in which event the adhesive will be immediately dried and hardened. From the foregoing it will be understood that this step in the method results in a superficial union of the strips or plies. In other words the strips or plies are united to each other through a medium presented only upon their contacting faces as distinguished from a union by stitching or some other medium penetrating or passing entirely through the plies and while at the present time I consider the employment of an adhesive applied in a liquid or semi-liquid state to one or the other or both of the plies upon their mutually contacting faces, I may employ any other means found suitable for the purpose and, therefore, it is

my intention that the expression superficial means as employed in this specification and the appended claims is to be construed as including any means whatsoever which may be employed for uniting the plies face to face without penetrating or extending entirely through the said plies.

The other step in the method, and which step may be carried out previous, simultaneously with, or subsequent to the performance of the step above described, consists in printing or otherwise impressing upon the outer face of the facing ply 1, or the strip if the plies are initially in strip form, lines or designs simulating lines of stitching, and in the present instance the outer face of the ply 1 has printed or otherwise impressed thereon imitation lines of stitching indicated by the numerals 7, 8, 9 and 10, these imitation lines of stitching extending, respectively, opposite the zones of adhesive 3, 4, 5 and 6. The imitation lines of stitching above referred to may be printed by any suitable mechanism and if desired they may be forcibly impressed after the zones of adhesive have been applied and the plies or strips have been brought together, so as to assist in firmly uniting the plies or strips along the lines of the said zones. Also the character of the lines of imitation stitching may be greatly varied, the lines 8 and 9 in the present instance representing a quilting stitch and the lines 7 and 10 being of such nature as to represent an over-edge stitch. Of course, if desired, as a variation, more or less artistic floral designs may be impressed along the lines 8 and 9, or these lines of stitching may be made to take a wavy or looped or other artistically appearing course. In any event it is preferable that the impressions representing the lines of stitching be in a distinctive color so as to appear in an attractive manner upon the facing ply 1.

I have found that by employing the proper sort of adhesive, the plies comprising the blank may be united to each other in substantially as secure a manner as though actually stitched together. However, if desired the modification illustrated in Figs. 4 and 5 of the drawings may be resorted to. In these figures the numeral 11 indicates an actual line of stitching of the ordinary character run through the plies immediately inwardly of their outer edges and consequently touching the bights of the loops which are printed upon the face of the facing ply 1 at this edge of the ply to imitate the line of over-edge stitching usually employed. In this manner the outer edges of the plies comprising the blank may be firmly united by a line of stitching without, however, resorting to an over-edge stitch, and yet the finished article will have the appearance of being provided with such a

stitch at its outer edge. However, as stated the line of stitching 11 is not needed if the proper sort of adhesive is employed.

As heretofore stated, when lines of stitching, or more specifically a quilting stitch, are run along the lines corresponding to the lines 8 and 9 above referred to, the stiff cloth plies are so weakened by the needle punctures that the cuff as a whole is flexible or 10 may be readily bent or creased along these lines in the same manner that a piece of paper may be readily bent, folded, or its parts separated, along a line of perforations formed therein and also in the same manner 15 as a sheet of metal may be readily bent or folded along a scored line or a line following a deeply cut groove. Thus in uniting the facing and lining plies by lines of stitching extending along the intermediate portions 20 of the plies, the cuff blank is greatly weakened and its stiffness is impaired rather than enhanced. On the other hand in uniting these plies by longitudinally extending zones of adhesive in the manner above described, the plies are not only securely held 25 together throughout their intermediate portions, but the stiffness of the cuff blank is greatly increased and it is better enabled to hold its shape even when crushed. Furthermore, 30 there is no weakening of the material such as is incident in the former instance, to the penetration of the material by the sewing machine needle. Another decided advantage possessed by the article embodying the invention and presented by the method 35 of the invention, is that the completed article produced in accordance with the invention will bear imitations of lines of stitching entirely regular in form and attractive 40 in appearance as distinguished from the irregularities which must result when the plies of such an article are actually stitched together and the stitches have been dropped and the plies restitched.

In the previous description reference has been had to a cuff blank comprising two or more plies, but by following out the last described step only of the method, a single ply blank such as shown in Figs. 7 and 8 may be produced, this blank comprising, as stated, but a single ply of heavy relatively stiff material having printed or otherwise impressed upon its outer face the imitation lines of stitching heretofore referred to.

From the foregoing description of the article and the method whereby it is produced it will be understood that by carrying out the method I am enabled to produce a cuff blank in which the plies will be substantially as securely united to each other as though stitched together and which blank will have the appearance of being neatly and artistically stitched. At the same time it will be apparent that by uniting the plies to each other through the em-

ployment of longitudinally extending zones of adhesive I not only avoid weakening the plies through needle punctures but on the other hand greatly reinforce the plies along their lines of union, considerably stiffen the 70 blank as a whole, and at the same time provide means for maintaining the shape of the blank and restoring it to its proper shape after being crushed. It will also be obvious that not only do I attain the new results 75 and advantages aimed at, but I also provide for a great saving of material and labor, and a great saving in the expense incident to the operation and upkeep of expensive sewing machines so that both the wholesaler and the manufacturer may obtain greater profits and the purchaser may, at a lower cost, obtain a gauntlet having cuffs more attractive in appearance than the ordinary stitched cuffs and equally as durable. 80

In the appended claims I will refer to the article as an apparel blank and it is to be understood that by this expression I intend to include an apparel blank of any nature whatsoever although as heretofore 90 stated the invention is designed primarily to be followed in the production of cuffs for gauntlets.

Having thus described the invention, what is claimed as new is:

1. As a new article of manufacture, an apparel blank comprising superficially united plies of material, one of said plies having upon one face in a distinctive color an imitation of stitching. 100
2. As a new article of manufacture, an apparel blank comprising superficially united facing and lining plies of material, the facing ply having upon its outer face in a distinctive color an imitation of stitching. 105
3. As a new article of manufacture, an apparel blank comprising plies of material superficially united at one edge, one of said plies having upon one face at the said edge an imitation of stitching. 110
4. As a new article of manufacture, an apparel blank comprising plies of material superficially united along relatively narrow zones, one of said plies having upon one face an imitation of stitching extending opposite said zones. 115
5. The method of producing an apparel blank which includes the steps of superficially uniting plies to comprise the blank, and impressing upon a face of one of the plies, an imitation of stitching in a distinctive color. 120
6. The method of producing an apparel blank which includes the steps of superficially uniting the edges of plies which are 125 to comprise the blank, and impressing upon one face of one of the plies at the said edge, an imitation of stitching.
7. As a new article of manufacture, an apparel blank comprising plies superficially 130

united along one edge, one of said plies having upon one face at the said edge an imitation of stitching, and a line of stitching run through the plies substantially at the line of imitation stitching.

8. The method of producing an apparel blank which includes the steps of superficially uniting an edge of plies which are to comprise the blank, impressing upon one face of one of the plies at the said edge an

imitation of stitching, and running a line of stitching through the plies substantially along the line of imitation stitching.

9. As a new article of manufacture, a ply of an apparel blank bearing upon one face in a distinctive color an imitation of stitching.

In testimony whereof I affix my signature.

FRANK R. EVANS. [L.S.]
